APPARATUS AND METHOD FOR
CONSTRUCTION OF BASKETS

Ralph Lewis Scanlan, Weymouth, Ohio

Application August 3, 1940, Serial No. 350,829

10 Claims. (Cl. 1—13.6)

My invention relates to basket making machinery and method.

In the manufacture of baskets, slats or strips of thin wood or other suitable material are first assembled and secured together to form a flat mat. In this mat the slats are disposed transversely of each other, some extending longitudinally and others extending laterally, and in the usual form of mats the longitudinal and lateral slats are interwoven.

The flat mat is constructed into a rectangularly shaped basket by bending two longitudinal edge portions at right angles to the remainder of the mat to form the bottom and two longitudinal side walls of the basket, and by bending and over-lapping the ends of the mat at right angles to both the bottom and side walls of the basket to form the end walls of the basket. The bent and over-lapped ends of the mat are then stapled or nailed together in the conformed position to secure the mat in the conformed shape of the basket. Relatively narrow edge strips are customarily secured to the longitudinal edges of the flat mat and upon the bending and over-lapping of the ends of the mat to form the end walls, the edge strips are over-lapped and stapled or nailed together and some of the slats are bent under, or secured by staples or nails to, the over-lapped edge strips which thus adds strength and rigidity to the construction of the basket.

The most satisfactory manner of properly securing the slats and edge strips together in over-lapped relationship upon the forming of the basket in the described manner is by stapling. In stapling, staples are driven through the layers of thin wood in over-lapped relationship and the inner ends of the staples after being driven through the wood are clinched or "turned over" by the resistance and inclined surface of a clinch-block or anvil against which the ends of the staples are driven. Unless the clinch-block is properly positioned at the correct angle relative to the staples driven through the wood the staples will not be properly clinched or turned over. The plane of the clinch-block should be substantially perpendicular to the longitudinal dimension of the staple. The clinch-block in addition must be relatively rigid to assure stability under the impact of the staple driven thereagainst. Unless the clinch-block is thus properly located in position at all times and is firmly secured in rigid position the staples will not always strike the slightly inclined surface of the clinch-block at the proper angle and will not be properly clinched or "turned over" closely against

the wood through which the staple has been driven. Therefore, in the manufacture of baskets it is extremely important and vitally necessary that apparatus be provided for the proper clinching of the staples driven through the over-lapped layers of wood to assure a secure fastening of the parts of the conformed mat in the shape of the basket.

An object of my invention is the provision of 10 an improved basket making machine for the forming and stapling of mats in the shape of a basket.

Another object of my invention is the provision 15 of apparatus assuring the proper clinching of staples driven into a basket.

Another object is the provision for forming the basket, the carrying of the formed basket into 20 stapling position and the stapling, including the clinching of the staples, of the formed basket at said stapling position.

Another object is the provision of basket forming apparatus of improved construction.

Another object is the provision for forming 25 the basket on a form-block, moving the form-block and basket formed thereon to a stapler and clinch-block and stapling the formed basket on the form-block with the stapler and clinch-block.

Another object is the provision of apparatus 30 having a stapler and clinch-block permanently mounted at one fixed position, a device for forming a basket and carrying means for carrying the device and formed basket to the stapler and clinch-block for securing of the staples in the basket.

Another object is the provision for stapling a 35 basket formed on, and carried by, a form-block against a rigid clinch-block fixed permanently in position relative to the stapler.

Another object is the provision of apparatus 40 for forming a basket and holding the basket in formed position during stapling of the basket.

Another object is the provision of an improved 45 method of basket making.

Other objects and a fuller understanding of my invention may be had by referring to the following description and claims, taken in conjunction with the accompanying drawing, in which:

Figure 1 is a side elevational view of my improved machine in a first operating position;

Figure 2 is a view similar to that of Figure 1 and illustrates the machine in a second operating position;

Figure 3 is a view similar to that of Figures 1 and 2 and illustrates the machine in a third operating position;

Figure 4 is a plan view of the form-block and associated conforming member incorporated in my machine and shows details of construction; and

Figure 5 is a detail sectional view of a portion of the form-block incorporated in my machine taken through the line 5-5 of Figure 4.

The description of the invention is made in conjunction with the several views of the accompanying drawing illustrating one form of the embodiment of the invention.

A standard 12 is mounted in upright position on the floor 11 and a stapling machine or stapler of which the lower portion is shown generally by the reference character 13 is mounted upon the standard 12. A metal clinch-block or anvil 14 is carried by, and extends outwardly from, the stand 12 directly below, and at a small distance from, the stapler 13. The outer corners of the extended end of the clinch-block 14 are chamfered or rounded, as at 15. The clinch-block 14 is disposed on a horizontal plane in respect to the vertically disposed stapler 13 thereby assuring that the clinch-block is at a right angle to the staple ejected and driven by the stapler. The surfaces of the clinch-block against which the staples are driven are slightly inclined in order to start the staples to "turn over" and clinch, as is generally done in stapling machines. The clinch-block being permanently mounted in juxtaposition to the stapler is rigid and stable and therefore always meets the staples driven thereon in the same manner and insures uniform clinching of the staples.

A frame comprising the horizontal rocker arm 16, the upright arm 18 and the upright arm 20 is positioned in front of, and at an operating distance from, the stapler. The rocker arm 16 is journaled upon a bearing support 17 which in turn is anchored to the floor 11. By means of the pivot provided at the bearing support 17 the whole frame may be swung thereon toward and away from the stapler. In Figure 1 the frame is shown as swung away from the stapler and in Figure 3 the frame is shown as swung toward the stapler. The coil spring 43 between the standard 12 and arm 18 resiliently urges the frame toward the standard 12 and helps counter-balance the weight of the frame and parts carried thereby when inclined or tilted back away from the stapler as in Figure 1.

A form-block 27 is mounted to the upper end of the arm 18 by the swivel connection 19 in such manner that the form-block may be freely rotated on the connection 19 to reverse the position of the ends of the form-block. The form-block 27 has exterior surfaces on five sides conforming to the shape of the basket to be formed, the back of the form-block conforming to the bottom of the basket, the two longitudinal sides of the form-block conforming to the side walls of the basket and the end portions of the form-block conforming to the end walls of the basket. The form-block is preferably made of wood but may be made of any other suitable material.

In each opposite end portion of the form-block 27 there is a part cut-away to form recesses 28 in the ends of the form block. As shown in Figures 4 and 5 the recesses are positioned in corners of the form-block to extend in from both the end and the front wall of the form-block. In Figure 4, the basket formed around the form-block 27 is indicated by the dot-dash lines on three sides of the form-block.

A plate 29, preferably made of steel, is secured to each of the opposite ends of the form-block by screws 37 in such manner as to extend across and over the recesses 28. The plate 29 is cut away at the regions of the point of stapling and as the basket is stapled at three points upon each end of the basket, in the particular example illustrated in the drawing, the plate is cut away to form the two cut-out portions 30 and the intermediate cut-out portion 31.

Two finger portions 32 are formed by the removal of the cut-out portions 30 and 31 and these two finger portions 32 project outwardly a short distance from the form-block 27. The outer extreme end of each finger portion 32 is bent upwardly to form the back-stops 34. A U-shaped holding member 35 is hingedly connected to the ends of the two fingers 32 by means of the hinges 33 in the manner illustrated in Figures 4 and 5. A spring 36 between the holding member 35 and a back-stop 34 resiliently urges the holding member to the upright position against the back-stops 34 shown in Figure 5.

By manually seizing the end of the holding member 35 and swinging it down toward the form-block 27, wood slats or strips positioned on top of the end of the form-block 27 are firmly clamped between the holding member 35 and form-block 27. The disposition of the parts is such that the holding member may be lowered in clamping position and at the same time the wood slats or strips over the open cut-out portions 30 and 31 are unobstructed and staples may be driven into the wood at those points. The open space in the U-shaped holding member 35 substantially co-incides with the opening of the cut-out portion 31 and the stapling of the wood may be done through the open space in the holding member 35 while lowered in clamping position.

The upright arm 20 of the three-member frame heretofore referred to is hingedly connected to the rocker arm 16 by means of the hinge 42 in such manner that the arm 20 may swing on the hinge 42 toward and away from the arm 18 and form-block carried thereon. A toggle mechanism 46 connects the arm 20 to the arm 18 at a distance from the rocker arm 16 to control the movement of the arm 20 relative to the arm 18. The spring 45 between the toggle mechanism 46 and rocker arm 16 resiliently urges the toggle mechanism into the extended position shown in Figure 1, that is, slightly down below dead center and thus in locked condition. A fixed upright member 48 extends up from the floor 11 and is so positioned as to contact the toggle mechanism upon the swinging of the entire frame on the pivot bearing 17 toward the stapler and thus to trip or unlock the toggle mechanism and to cause it to move from the position of Figure 1 to the position of Figure 3. The adjusting mechanism 47 provides for the adjustment of the toggle and the determination of its locked position beyond dead center. A spring 44 connecting the arm 20 to arm 18 resiliently urges the arm 20 toward the arm 18 upon the tripping or unlocking of the toggle mechanism. As the spring 44 is stronger than the spring 45 the arm 20 will be moved toward the arm 18, as in Figure 3, upon the tripping or unlocking of the toggle mechanism.

Upon the upper end of the arm 20 a conform-

ing member 22 is mounted by means of the swivel connection 21, the conforming member 22 being carried on the arm 20. The conforming member 22 has side wings, comprising angular wing portions 23 and 25, hingedly connected to its longitudinal edges by means of the hinge connections 24. The wing portions 23 and 25 are at a fixed right angle to each other to provide that upon the backward swinging of the wing portions 25 toward the conforming member the outer wing portions 23 are swung in toward each other and to thus clamp an object therebetween.

In the construction of the basket in the embodiment here illustrated a mat is made in the flat by assembling a plurality of longitudinal wood veneer slats 39 and lateral veneer slats 40, interwoven or secured together in transverse position. Edge strips 41 of narrow pieces of veneer are secured to the longitudinal edges of the assembled mat, preferably on both front and rear faces of the mat. The parts of the mat are usually secured in assembled position by stapling while disposed on a flat rack slid under a stapling machine. The mat in flat form is then ready to be conformed and secured into the shape of a basket.

An operator standing in front of the machine facing the stapler places a flat mat intermediate of the form-block 27 and conforming member 22 while the machine is in the open position shown in Figure 1. The hands of the operator push the mat against the form-block 27 and bend the edge portions of the mat in against the longitudinal sides of the form-block 27 whereby the mat is longitudinally bent into the form illustrated in Figure 1. In this stage of the forming of the basket the bottom and two side walls of the basket are formed but the ends of the basket are open, the ends of the mat extending straight up and down.

In pushing the mat against the form-block 27 and bending the sides of the mat in toward the sides of the form-block, the operator's hands embrace the form-block therebetween and push or press the form-block toward the stapler. This forward movement of the form-block tilts the supporting frame upon the pivot bearing 17 sufficiently to cause the member 48 to trip or unlock the toggle mechanism 46. Upon the tripping or unlocking of the toggle mechanism 46 the spring 44 pulls the arm 20 and conforming member 22 toward the arm 18 and form-block 27. The conforming member 22 is thus pressed tightly against the form-block 27 with the basket mat therebetween. The inner wing portions 25 of the hinged wing members are forced back against the conforming member 22 and cause the outer wing portions 23 to swing in tightly against the longitudinal side of the basket conformed to the side of the form-block 27 and thus clamp the basket tightly to the form-block and hold it in proper form. Figure 2 illustrates this stage of the operation with the basket mat partially conformed and clamped between the form-block 27 and conforming member 22. Small springs not shown tend to keep the wing members in spread-out or spaced position except when forced together in clamping action by the movement of the conforming member toward the form-block.

The end walls of the basket are next formed, one end being formed at a time. The upper end of the basket is first formed. The ends of the longitudinal slats 39 which are disposed along

the sides of the basket are bent in toward each other and over-lapped down upon the upper end of the form-block. The ends of the longitudinal slats 39 which are disposed along the bottom of the basket are then bent forward and down to over-lap the previously bent ends. The ends of the edge strips 41 are then bent inward toward each other and down to over-lap the previously bent slats. The end wall of the basket is thus formed by bending and over-lapping of the parts of the mat but is not secured in formed position at this stage but is merely held in the conformed position by the hands of the operator.

The upper holding member 35 is next swung toward the operator to clamp the end wall of the basket in conformed position against the top end of the form block.

By pressing the end of the holding member down and swinging the form-block and conforming member, with conformed basket therebetween, forward toward the stapler the machine is moved to the position illustrated in Figure 3, the frame which carries the form-block and conforming member tilting on the pivot bearing 17 toward the stapler. The clinch-block or anvil 14 enters the upper recess 28 in the form-block, which recess is proportioned to accommodate the clinch-block. The chamfering of the outer end 15 of the clinch-block helps assure the free entry of the clinch-block in the recess to substantially fill the same. As the form-block swings in an arc and the clinch-block is in fixed horizontal position the chamfering or rounding of the corners and edges of the clinch-block facilitates the movement of the form-block to and from the clinch-block.

The stapler is then operated to drive staples through the overlapped slats and strips at the end of the conformed basket. The staples do not meet or contact the form-block by reason of the cut-out portions 30 and 31 in the plate 29 and the open space in the holding member 35 but rather are driven through the wood veneer of the basket and directly against the clinch-block 14 extending into the recess 28. The impact and force of the driven staples is received by the relatively stable clinch-block rather than by the relatively unstable form-block. The contacted surface of the clinch-block is disposed to turn over and clinch the protruding ends of the staples driven against the clinch-block and thus tightly secure the turned over ends of the staples against the wood veneer.

By operating the stapler as the form-block and clinch-block are nested together as shown in Figure 3 the upper end wall of the basket held in position by the upper holding member 35 will be firmly secured in conformed shape, the parts being held together by the staples. After stapling one end wall of the basket as described, the form-block, basket and forming block are retracted from the position of Figure 3 to that of Figure 2 by tilting the frame back away from the stapler. When in the position of Figure 2 the form-block 27 and conforming member 22 are rotated upon the swivel mountings 19 and 21, respectively, to reverse the positions of the ends of the basket held thereby. Upon thus bringing the other end of the basket uppermost the upper end wall of the basket is formed and stapled in the same manner as that described for the first mentioned end wall of the basket. The rotating of the basket upon the swivel connections facilitates the quick fabrication of the basket by bending and stapling.

In machines in which it is attempted to clinch the staples against the form-block rather than as herein described it is found that the form-block being rotatable is not always brought under the stapler in exact horizontal position but is often slanting one way or the other. Unless the staples are driven against a surface that is always in perfect fixed alignment the staples are not properly clinched. Attempts to lock the rotatable form-block in proper rotated position have not satisfactorily met this requirement because of "play" in the locking mechanism and also because the rapid action of the operator does not lend itself to accuracy in always having the form-block locked in proper rotated position before pushing under the stapler. Moreover, the mechanism for carrying the form-block to and from the stapler and for rotating the form-block is inherent relatively unstable. As a stable or rigid clinch-block is necessary for efficient clinching of the staples my apparatus meets that requirement. Therefore, by the fabrication of baskets with apparatus embodying my invention uniformly proper stapling is accomplished, there being an assurance that the staples are fully and properly clinched. There is an increase in number of baskets which may be turned out as well as in the quality of the work done.

Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. A machine for forming baskets from flat mats of basket material comprising, in combination, a form-block upon which the mat is conformed, said form-block having opposite end portions over which the ends of the said mat are over-lapped to form opposite end walls of said basket, a conforming member for holding the said mat against said form-block, said conforming member having swingable wing members pivotally mounted thereon for holding the mat in conformed position against the sides of the form block, a stapler mounted in juxtaposition to said form block, a clinch-block mounted below, and spaced from, said stapler, a support frame having a first arm for supporting said form-block and a second arm for supporting said conforming member, the form-block being rotatably mounted on said first arm to reverse the positions of said end portions of the form block, said second arm being movable relative to said first arm to move the conforming member toward and away from the form-block, the said support frame being movable relative to said stapler and clinch-block to move the form-block and conforming member toward and away from the stapler and clinch-block, said form-block having a recess formed in each said opposite end portion thereof to accommodate said clinch-block upon moving the form-block toward the stapler and clinch-block to position said over-lapped end of the mat between said stapler and said clinch-block, said stapler driving staples through said over-lapped end and against said clinch-block.

2. The combination of a stapler, a clinch-block mounted below, and spaced from, the stapler, a form-block about which a mat is conformed to the shape of a basket, said form-block having a recess formed therein at the locality

- where the conformed mat is stapled and extending parallel to a side of the basket to be stapled, and supporting means for supporting said form-block, said supporting means being movable in a direction substantially parallel to said side of the basket to be stapled to move the form-block and conformed mat thereon relative to the stapler and clinch-block from basket forming position to stapling position, the clinch-block extending substantially parallel to said side of the basket to be stapled and into the recess in said form-block when in stapling position to clinch the staples driven through the basket mat on the form-block by said stapler.
3. The combination of a stapler, a stationary clinch-block mounted in juxtaposition to the stapler, and a form-block upon which a mat is conformed to the shape of a basket, said form-block being movable toward and away from said stapler in a direction parallel to the sides of said basket, said form block being cut away to accommodate the said clinch-block upon moving the conformed mat on the form-block forward toward the stapler to stapling position adjacent the stapler, the clinch-block clinching the staples driven through the conformed mat on said form block.
4. The combination of a stapler, a relatively stable fixed clinch-block mounted under, and spaced from, the stapler, and a relatively unstable movable form-block adapted to carry a basket formed thereon to stapling position under the stapler, the said form-block being formed to permit said clinch-block to extend intermediate the basket and form block for the clinching of staples driven through the basket and against the clinch-block.
5. The combination of a stapler, a clinch-block carried by, and spaced from, said stapler, a form-block adapted to carry a basket conformed thereon, said form-block having a recess disposed intermediate the said basket and said form-block, said recess being adapted to receive said clinch-block upon movement of the form-block into stapling position adjacent said stapler, and carrying means for carrying said form-block into and, and out of, stapling position adjacent said stapler, the stapler stapling the basket on said form-block against the clinch-block in said recess.
6. The combination of a stapler, a fixed clinch-block and a movable form-block, said form-block being formed to accommodate said clinch-block extending intermediate the form-block and a basket conformed thereon upon movement of the form-block into stapling position adjacent the stapler, the stapler driving staples through the basket on the form-block against said clinch-block.
7. A form-block for the making of stapled baskets, said form-block having an outer surface in the contour of a basket for the forming of the basket thereon, the form-block being cut-away from said contour in the vicinity of the basket at point of stapling to provide an open space intermediate the said basket and form-block, said open space accommodating a clinch-block extendable therein for the clinching of staples driven through the basket.
8. A form-block for the making of baskets stapled at opposite ends, the form-block having a back conforming to the bottom of the basket, longitudinal sides conforming to the side walls of the basket and end portions conforming to the end walls of the basket, said form-block be-

ing cut away at each of said end portions to form a recess below the plane of each said end portion, a plate secured to the form-block, at each of said end portions and extended across said recess therein, said plate being cut away at the location of the stapling of the basket, the recesses in the form-block accommodating a clinch-block extendable therein upon movement of the form-block into stapling position and withdrawable therefrom upon movement of the form-block from stapling position, the cut-away portions of the said plates providing for stapling against the clinch-block the end walls of the basket conformed to shape by the end portions of the form-block and plates thereon.

9. The combination of a form-block having a back, sides and ends in the shape of a basket conformed thereon, a conforming member movable relative to the form block for holding the conformed basket to the back and sides of the form-block, and holding members carried by the form-block at the ends thereof for holding the

conformed basket to the ends of the form-block, said form-block having open spaces formed in the ends thereof for receiving a clinch-block mounted adjacent a stapler upon moving the form-block to stapling position at a stapler, said open spaces permitting the stapling of the basket formed on the form-block and clinched independently of the form-block.

10. The method of constructing a basket comprising: the steps of making a basket mat in the flat, the steps of bending the mat around a form-block into the shape of a basket at a distance from a stapler, clamping the conformed mat to the form-block in said shape, moving the conformed mat on said form-block to said stapler in a direction parallel to a side of the basket to be stapled, driving staples through the conformed mat to secure it in the shape of the basket, and clinching said staples to the basket independently of said form-block.

RALPH LEWIS SCANLAN.
